UNITED STATES PATENT OFFICE.

AUGUST E. ROEVER, OF BROOKLYN, NEW YORK, ASSIGNOR TO JAMES B. KIRBY, OF CLEVELAND, OHIO.

VACUUM-CLEANER NOZZLE.

1,191,999.

Specification of Letters Patent. Patented July 25, 1916.

Continuation in part of application Serial No. 859,952, filed September 3, 1914. This application filed October 26, 1915. Serial No. 57,911.

To all whom it may concern:

Be it known that I, AUGUST E. ROEVER, a citizen of the United States, residing at Brooklyn, in the county of Kings and State 5 of New York, have invented certain new and useful Improvements in Vacuum-Cleaner Nozzles, of which the following is a specification.

This invention relates to vacuum cleaner 10 nozzles, the object of the invention being to provide an improved nozzle thoroughly effective to take up threads and other debris of this general character and in which the thread-picking devices will be maintained 15 in their proper thread-picking positions during the movement of the nozzle over the surface to be cleaned.

The object of the invention, therefore, is the provision of an improved nozzle effective 20 for the purpose stated, which is simple in construction, inexpensive to manufacture, and reliable and durable in use.

In the drawings accompanying and forming part of this specification, Figure 1 is a 25 bottom view of one form of the nozzle having the present improvement applied thereto; Fig. 2 is a longitudinal sectional view taken in line 2—2, Fig. 1; Fig. 3 is a cross-sectional view taken in line 3—3, Fig. 1; and 30 Fig. 4 is a side view of one of the thread-removing devices shown in the other figures.

Similar characters of reference indicate corresponding parts in the several figures of the drawings.

35 In the present instance only so much of a vacuum cleaner is shown as is necessary to illustrate the present improvement, and therefore a part of the nozzle 2 of usual form is illustrated. This nozzle is provided 40 with the usual elongated opening 3 of suitable length and width to permit the use of the improved thread-removing devices. Carried in the opening of this nozzle is a lengthwise-extending rod 4 projecting into 45 openings 5 in the end walls of the nozzle, and located on this rod, which is pivotally supported for rocking movement, are a series of thread-removing devices 6, which are preferably fixedly secured to the rod, and 50 these thread-removing devices rock with the rod according to the direction in which the nozzle is shifted over the floor. These thread-removing devices 6 are formed of some soft flexible or pliable material, and

that found most efficient in use is rubber, 55 and each is made of a peculiar shape. Each comprises a member having a round under-surface which is adapted to rest on the floor and in practice projects preferably not beyond the lower lips or surface of the nozzle 60 and terminates in oppositely located points or teeth, and this member is provided with a shank 7 preferably narrower at its lower end than it is at its upper end, and this shank is provided with an opening 8 by 65 means of which each of these rubber devices is mounted upon the rod. These devices are located at intervals along the rod and the curved floor portion thereof terminates in sharp flexible points 9 at each side of the 70 shank, and in practice as the nozzle is shifted over the floor, for instance in a forward direction, (see arrow in Fig. 3), these members are rocked with the rod. This action is shown in Fig. 3 in dotted lines, and 75 as the nozzle is drawn backward these members are shifted forward so that the soft flexible points of the rubber quickly and readily pick up the threads and remove them from the floor, and this is materially 80 assisted by reason of the character of material of which these thread-removing devices are made, since the threads will adhere to the rubber as the devices rock back and forth in the movement of the nozzle over the floor 85 and are thus gathered and pulled off the floor so that the suction can draw them into the nozzle.

To maintain the thread-picking devices in their proper working positions, suitable 90 means is provided. In the present instance this consists of a pair of projections 10, one located at each end of the rod, and so located in the present instance that they will engage the side walls of the casing and thus maintain 95 the thread-picking devices in such position that their pointed ends will engage the face to be cleaned, see dotted lines in Fig. 3. Thus it will be observed that these limiting stops 10 engage one wall of the casing, 100 as the front wall thereof, when the nozzle is being pushed forward and the rear wall thereof when the nozzle is pulled backward, this change in position of the stops resulting from the rocking of the rod 105 due to the movement of the thread-pickers over the surface being cleaned, and that in each of these positions the thread-pickers

are maintained in such position that their pointed or toothed ends are in position to effectively pick up threads and other lint of similar kind as the nozzle passes back and forward over the surface being cleaned, so that there is no tendency of such thread-picking up devices to move out of their normal working position. Within the purview of my invention is any form of means which 5 will limit the rocking movement of the thread-picking devices on the rock shaft carrying the same.

It will be observed that in the operation of this improvement, while one set of teeth 10 are in position to remove threads and other lint from the surface being cleaned the opposite set of teeth have been carried into position where they are in raised position, so that they are subjected to the air stream, 15 whereby any adhering material thereon is readily removed and drawn into the nozzle.

It will be understood that the various details may be more or less modified without departing from the spirit and scope of this 20 invention.

I claim as my invention:

1. A cleaner nozzle having a lengthwise extending opening therein, and a plurality of thread-removing members suspended 30 within said nozzle and each having a tapered portion extending transversely of such opening.

2. A cleaner nozzle having a lengthwise extending opening therein, and a plurality of 35 rocking members spaced apart within said nozzle and each comprising a depending body portion provided at its lower end with thread-removing projecting portions and means for suspending said members to 40 permit the rocking thereof during the operation of the nozzle.

3. A cleaner nozzle having a lengthwise extending opening therein, a rod extending lengthwise thereof, and a plurality of flexible 45 rocking thread-removing members mounted upon said rod and spaced apart within said nozzle and each comprising a depending body portion provided at its lower end with oppositely extending projecting portions.

4. A cleaner nozzle having a lengthwise extending opening therein, a plurality of 55 rocking flexible thread-removing members suspended within said nozzle and each comprising a depending body portion having oppositely tapered portions, and means extending transversely through said flexible members for suspending the same for rocking movement during the operation of the 60 nozzle.

5. A cleaner nozzle having an opening 65 therein, rocking means suspended within said opening for rocking movement during the operation of the nozzle and having along said opening thread-removing point-

ed-end projections extending transversely to such opening.

6. A cleaner nozzle having an opening 70 therein, rocking means pivotally supported within said opening, said rocking means comprising a plurality of pairs of oppositely extending thread-removing projections located along said opening.

7. A cleaner nozzle having an opening 75 therein and a series of rocking members supported within said opening, each of said rocking members having a curved working surface terminating in oppositely located teeth formed of flexible material.

8. A cleaner nozzle having an opening 80 surrounded by a work-engaging surface, a rod located in said opening, and a series of thread-removing flat rocking devices carried upon said rod and having their under surfaces in the plane of said work-engaging 85 surface.

9. A cleaner nozzle having an opening 90 surrounded by a work-engaging surface, a rod located in said opening, and a series of flat flexible thread-removing rocking devices 95 carried upon said rod and having their under surfaces in the plane of said work-engaging surface.

10. A cleaner nozzle having an opening 95 surrounded by a work-engaging surface, a rocking rod located lengthwise within said opening, a series of flexible rocking members fixedly carried on said rod within said opening and each having a curved under surface located in the plane of said work-engaging 100 surface and terminating in oppositely located points.

11. A cleaner nozzle having an opening 105 therein, and a series of rocking members pivotally supported within said opening and spaced apart, each of said rocking members comprising a flat body portion having an edgewise extending pointed portion normally projecting transversely of the nozzle.

12. In a vacuum cleaner nozzle of the 110 type having an elongated inlet mouth surrounded by work-engaging jaws, an agitating device pivoted in said casing upon an axis parallel with said mouth, said device comprising a plurality of radial members 115 having flexible teeth projecting substantially tangentially of the circle drawn about the pivot axis and arranged to engage and comb the surface operated upon, and means for rotating said device about its pivot so as to raise said teeth from such surface and present them to the air stream.

13. A cleaner nozzle having an opening 125 therein, rocking devices pivotally supported within said opening, said rocking devices comprising a plurality of flat, toothed members, means operative upon changes in the direction of movement of the cleaner for rocking said devices to elevate certain teeth and depress other teeth, and stop means 130

to arrest such rocking movement and hold the depressed teeth in engagement with the work surface.

14. In a cleaner nozzle, a plurality of sets of lint pickers each having oppositely extending pointed ends, means operative upon changes in the direction of movement of the nozzle for lowering one set into engagement with the working surface and elevating the other set into the air stream for cleaning the

same, and stop means defining the limit of movement of such pickers both when lowered and raised.

Signed at Room 1822 Park Row Building, New York, in the county of New York and 15 State of New York.

AUGUST E. ROEVER.
